UNITED STATES PATENT OFFICE.

WILLARD F. RICHARDS, OF DEPEW, NEW YORK, ASSIGNOR TO GOULD COUPLER COMPANY, OF NEW YORK, N. Y.

SUPPORTING DEVICE FOR COUPLINGS.

1,213,542.

Specification of Letters Patent. Patented Jan. 23, 1917.

Application filed April 10, 1913. Serial No. 760,096.

To all whom it may concern:

Be it known that I, WILLARD F. RICHARDS, a citizen of the United States, residing at Depew, in the county of Erie and State of New York, have invented a new and useful Improvement in Supporting Devices for Couplings, of which the following is a specification.

This invention relates to supporting brackets or devices for pivoted couplers of the kind employed on railroad locomotives and locomotive tenders in which the coupler is pivotally connected so as to swing laterally to a bracket or socket that is fixed on the locomotive, tender or other railway rolling stock on which the coupler is used.

It has been customary to provide the supporting brackets for couplers of this sort with a part intended to support the coupler in front of its pivotal connection with the bracket for the purpose of relieving the pivotal connection from the wear incident to the weight of the overhanging coupler head and preventing the coupler from sagging or tilting downwardly from the intended horizontal position. Brackets have been provided for this purpose with an integral forwardly projecting shelf or part upon which a part of the coupler head is adapted to rest and slide during the swinging movements of the coupler. There is considerable wear on the supporting shelf and the part of the coupler head bearing thereon, but no provision is made for raising the coupler into and supporting it in its proper horizontal position in the event that the wear becomes so great as to permit an undesirable sagging or tilting of the coupler, and it becomes necessary to replace the bracket or the coupler or both, since the supporting shelf and lug are integral portions of the bracket and coupler.

The object of this invention is to provide a bracket or socket for pivoted couplers of this kind with a device which is adapted to partially support the weight of the overhanging coupler and relieve the pivotal connection from the consequent wear, and which can be readily adjusted to compensate for

any wear in the supporting device and co-operating part of the coupler head, and which can also be readily replaced at small expense if worn or broken and without requiring the replacement of the bracket. This is accomplished by providing in connection with the bracket or socket, to which the coupler is pivoted, a supporting shelf or part which is adapted to sustain the weight of the coupler in front of the pivotal connection and which is adjustable vertically relative to the bracket and is also adapted to be readily detached and replaced, when worn, by a new shelf or part.

In the accompanying drawings: Figure 1 is a side elevation of a locomotive coupler and supporting bracket therefor embodying the invention. Fig. 2 is a fragmentary plan view thereof. Fig. 3 is a front elevation of the bracket, the coupler shank being shown in section. Fig. 4 is a fragmentary sectional elevation in line 4—4, Fig. 1, of the adjusting means for the supporting shelf or part. Fig. 5 is a fragmentary elevation, partly in section, showing a slightly different adjusting means for the supporting shelf. Fig. 6 is a transverse sectional elevation thereof in line 6—6, Fig. 5.

A represents a coupler which may be of any usual or suitable construction, and B represents a bracket which is adapted to be bolted or otherwise secured to a locomotive, locomotive tender or other railway rolling stock, and to which the coupler is pivotally connected.

In the construction shown the coupler is provided with the usual short shank or draw bar *a* which extends into a socket or hollow portion *C* of the bracket in which it is pivotally secured by a vertical pivot pin *D* extending through registering holes in the coupler shank and in the top and bottom walls of the socket portion of the bracket. The bracket is preferably provided with an upright rear wall or attaching plate *c* connected by strengthening ribs *c'*, *c''*, respectively, to the top and side walls of the socket portion *C* which projects forwardly from the upright rear wall *c* of the bracket.

F represents the supporting shelf or part, which is adjustably and preferably detachably connected to the lower portion of the bracket B and projects forwardly therefrom beneath a portion of the coupler, which is adapted to rest and slide on the shelf in the swinging movements of the coupler. The coupler is of a shape commonly in use in which the bottom portion of the head 5 slopes downwardly and forwardly, or depends below the shank *a* in front of the bracket. The supporting shelf F preferably projects forwardly beneath the rear portion of this enlarged coupler head and 10 the coupler is provided with a depending lug or portion G adapted to bear and slide upon the shelf. The supporting shelf F shown is pivoted to the bracket to swing vertically, for instance by a horizontal pin *f* passing through hinge lugs *f'* at the opposite ends of the shelf and through a lug *f''* which depends from the bottom of the socket portion C of the bracket between the lugs *f'* on the shelf. The shelf has arms *h* 15 which extend rearwardly beyond the pivot pin *f* beneath the bottom of the socket portion of the bracket and are provided at their rear or inner ends with a part adapted to bear against the bottom of the socket portion of the bracket to prevent the forward 20 end of the shelf from tipping downwardly. Preferably the rearwardly projecting arms of the shelf are provided with an open-topped pocket or chamber *h'* in which is retained a block H adapted to bear against the under side of the socket portion of the bracket. The weight of the coupler head on the front end of the shelf prevents the rearwardly projecting arms of the shelf from 25 swinging downwardly away from the socket portion of the bracket far enough to permit the escape of the block H from the retaining pocket, the block being thus retained in place. The block H bearing upwardly 30 against the under side of the socket C holds the forward end of the shelf up, and the shelf thus provides a rigid support for the overhanging coupler head.

By raising the block H in the pocket *h'* 35 and thus depressing the rearwardly projecting arms *h*, the forward end of the shelf can be raised sufficiently to compensate for any wear thereon or on the lug *g* of the coupler, and thus prevent the sagging of the coupler. The block can be thus raised in the pocket *h'* by means of set screws I passing through the bottom of the pocket, as shown in Figs. 1-4, or if preferred the block can be removed and one or more shim plates 40 K placed in the pocket beneath the block, as shown in Figs. 5 and 6. The block H can be removed for this purpose, either by detaching the shelf F, or by removing the coupler and lifting the forward end of the shelf.

65 *i* represents lock nuts for the set screws I.

Any other suitable adjusting means for the shelf could be used.

If the shelf F or the lug *g* of the coupler head become unduly worn, or the shelf becomes broken, the shelf can be detached from the bracket B by removing the pivot pin *f* and replaced by a new shelf at small expense.

I claim as my invention:

1. The combination with a car coupler, 75 and a bracket to which said coupler is pivoted to swing laterally, of a shelf on which said coupler is adapted to rest in front of the coupler pivot, said shelf being pivoted to said bracket so as to be vertically adjustable, and means for holding said shelf at different elevations, substantially as set forth.

2. The combination with a car coupler, 85 and a bracket to which said coupler is pivoted to swing laterally, of a shelf which is pivoted to said bracket so as to be vertically adjustable, said shelf having a portion extending forwardly from its pivot which partially supports the coupler, and a portion extending rearwardly from the shelf pivot adapted to bear upwardly against said bracket for holding the shelf in supporting position, substantially as set forth.

3. The combination with a car coupler, 95 and a bracket to which said coupler is pivoted to swing laterally, of a vertically adjustable device for partially supporting said coupler, said device being pivoted to said bracket and having a shelf portion extending forwardly from the pivot of said device 100 beneath a portion of the coupler, and an arm extending rearwardly from the pivot of said device, and means carried by said arm and adapted to bear against said bracket for holding said device in supporting position, 105 substantially as set forth.

4. The combination with a car coupler and a bracket to which said coupler is pivoted to swing laterally, of a vertically adjustable device for partially supporting said coupler, said device being pivoted to said bracket and having a shelf portion extending forwardly from the pivot of said device 110 beneath a portion of the coupler, and a pocket in rear of the pivot of said device, 115 and a block which is adapted to bear upwardly against said bracket and is vertically adjustable in said pocket, substantially as set forth.

5. In a coupler pocket, a shelf adapted to 120 engage and support a portion of a coupler head and having a pivotal connection with the pocket, and adjusting means for supporting the engaging portion of the shelf at varying heights.

6. In a device of the class described, the combination of a coupler pocket having a pivot bearing and an abutment portion, a shelf having bearings intermediate its ends, one portion of the shelf lying beneath said 130

abutment portion, another portion of said shelf extending forward to underlie and support a coupler, and a pin passed horizontally through said bearing in said pocket 5 and through the bearings in said shelf, substantially as described.

Witness my hand, this 7th day of April, 1913.

WILLARD F. RICHARDS.
